(57) CLAIM

I claim the ornamental design for a pillow with mesh striping, as shown and described.

DESCRIPTION

FIG. 1 is a front, top, right perspective view of a pillow with mesh striping showing our new design.

FIG. 2 is a top face view of FIG. 1;

FIG. 3 is a bottom face view of FIG. 1 and is identical to the top face view of FIG. 2;

FIG. 4 is a front face view of FIG. 1;

FIG. 5 is a rear face view of FIG. 1 and is identical to the front face view of FIG. 4;

FIG. 6 is a left face view of FIG. 1; and,

FIG. 7 is a right face view of FIG. 1 and is identical to the left face view of FIG. 6.
